(Cl. D58—25)

FIG. 1 is a side elevational view of the jar embodying my new design, the jar having the same appearance from all sides;

FIG. 2 is a bottom view of the jar shown in FIG. 1, dotted lines being employed to indicate that the successive upwardly extending ribs are continued entirely around the jar.

FIGURE 3 is a fragmentary horizontal transverse cross sectional view taken on lines 3—3 of FIGURE 1;

FIGURE 4 is a similar cross sectional view taken on line 4—4 of FIGURE 1;

FIGURE 5 is a similar cross sectional view taken on line 5—5 of FIGURE 1; and

FIGURE 6 is a fragmentary longitudinal vertical cross sectional view taken on line 6—6 of FIGURE 1.

The upwardly tapered panels which are successively arranged around the entire top section of the jar preferably are slightly dished in or concaved transversely.

The dominant features of my design reside in the portions shown in full lines.

I claim:

The ornamental design for a jar, as shown and described.
